APPARATUS FOR INSPECTING STAKED SYRINGES

Robert J. Myers and James R. Sager, Toledo, Ohio, assignors to Owens-Illinois, Inc., a corporation of Ohio

Filed Dec. 13, 1965, Ser. No. 513,444
5 Claims. (Cl. 209—73)

ABSTRACT OF THE DISCLOSURE

The inspection and sorting of staked syringes is carried out by conveying the syringes in succession through an inspection station where air under pressure is introduced into the open end of the syringe and the air flow is sensed at the exit end of the needle. If the exiting air flow velocity is insufficient, the defective syringe is removed from the conveyor at the sorting or reject station. Switch means are provided for turning the gauging air on and for triggering the removal of a defective syringe.

This invention relates to apparatus for inspecting staked syringes to determine that the needles are not plugged or that the diameter of the passage through the staked syringe is of sufficient size.

More particularly, this invention relates to apparatus for detecting plugged, staked syringes and for rejecting those staked syringes which are not properly made. Syringes of the type which are being checked by the present invention are of the type in which a glass barrel portion has a needle cemented in an opening in one end thereof. The process and apparatus by which the needle and barrel are assembled is disclosed in Walkden application S.N. 491,268, filed Sept. 29, 1965, assigned to the assignee of this application, and entitled, "Assembling Hypodermic Needles and Barrels."

As will sometimes happen in the operation of automatic machinery for assembling parts, and in particular in this situation where the needles are to be cemented in the barrel, there is the possibility that the mechanism will, in some fashion, be disrupted in its operation resulting in the delivery of syringes without needles or assembled syringe barrels and needles which are plugged by the cement or epoxy. Furthermore, it is possible that some of the needles will be partially plugged.

With the foregoing in view, it is an object of this invention to provide apparatus for inspecting staked syringes for plugged or absent needles.

It is an additional object of this invention to provide apparatus for inspecting staked syringes and to reject those which are defective.

It is a still further object of this invention to provide apparatus for inspecting a plurality of staked syringes in series and to separate the acceptable syringes from the defective ones.

Other and further objects will be apparent from the following description taken in conjunction with the annexed sheets of drawings, wherein:

FIG. 1 is a perspective view of the apparatus of the invention for inspecting and sorting staked syringes;

FIG. 2 is a front elevational view of the apparatus of FIG. 1;

FIG. 3 is a schematic, block diagram of the inspecting portion of the invention; and

2

FIG. 4 is a circuit diagram of the electrical components forming a part of the invention.

In the following description the term "staked" syringes is used when referring to the complete syringe comprising a glass barrel and affixed needle. The needles and barrel are joined together by a suitable cement such as an epoxy resin and in use are expected to be disposable after a single use.

Referring now to FIGS. 1 and 2, the apparatus of the invention comprises a chain conveyor 10. The conveyor is of the type disclosed in the above-referred-to Walkden application and generally comprises a series of chain links, of which syringes barrel engaging clips 11 form a part. The clips, as shown, comprise a pair of spring arms within which the barrel portion B of the staked syringes are held and conveyed in a substantially straight line, with the axis of the barrel extending generally vertical. Each barrel, as it comes from the assembly apparatus, is intended to have a needle N cemented in and carried by the barrel portion B with the axis of the needle intended to be substantially co-axial with the vertical axis of the barrels B.

As the syringes are conveyed by the chain 10 from the right to the left, as viewed in FIGS. 1 and 2, they will arrive at an inspection station where they are positioned vertically above an air nozzle 12. The nozzle 12 is connected to a solenoid valve 13 and a pressure regulator 14 (see FIG. 3). Air under pressure from a suitable source is introduced to the nozzle 12 under control of the regulator as to pressure and under the control of the solenoid 13 as to period of operation.

As the syringes reach the inspection station shown in FIGS. 1 and 2, wherein the syringe is in axial alignment with the nozzle 12, a switch 15 having an actuating arm 16 is engaged by the needle N and operates the solenoid valve 13 to turn on the air flow through the nozzle 12.

Positioned vertically above and in axial alignment with the nozzle 12 is a pressure switch 17. This switch may be of the type manufactured by Fairchild Controls under the designation "Faircon PSF 100." As shown in FIGS. 1 and 2, the pressure switch 17 is mounted on a supporting bracket 18 so that the switch is mounted over the run of the chain 10 and its opening 19 is in alignment with the nozzle 12. Thus it can be seen that when a syringe moves into position above the nozzle 12 and the syringe has a needle attached thereto, the needle will trip the switch 15 turning on the air under pressure in the nozzle 12 and the pressure switch 17 will sense whether there is a flow of air exiting from the needle. The switch 17 will operate on a predetermined air flow velocity. Obviously, if there is insufficient air flowing through the needle, the switch 17 will not be actuated or if there is no flow whatsoever, the switch 17 will not be actuated. Furthermore, if there is no needle carried by the barrel, the switch 15 will not be actuated and thus the air under pressure will not be fed through the nozzle 12.

In order to ensure that the staked syringes are in the proper position at the time they are tested, a guide rail 20 is provided which will engage the barrel portion of the staked syringes and a cam surface member 21 will engage the needle portion of the syringes. The cam surface 21 has its forward portion positioned such that it will engage the needle and ensure that the needle will be in alignment with the opening 19 into the pressure switch 17 and the guide rail 20, which will cause slight clockwise tilting of the syringe, will ensure that the needle will engage the cam surface of the member 21. In this

manner the staked syringes are ensured of being in the proper position at the time that the air is turned on by the tripping of the switch 15. It will be readily appreciated that the barrels as they are held in the clips 11, are capable of some small pivotal motion within the clips themselves since the clips are merely spring members.

After passing the inspection station, the syringes are carried to the left, specifically to the dotted line position shown in FIGS. 1 and 2, wherein the syringe barrel B, having an integral flange portion F, will pass between a pair of opposed members 22 and 23. As the barrel arrives at this position, the flange F will extend beneath the ends of the members 22 and 23, and a second switch 24, having an operating arm 25, will be engaged by the barrel portion B of the syringe. Operation of the switch 24 will actuate a solenoid valve 26 connected to an air supply line 27 connected to an air motor 28. The piston 29 of the air motor 28 is connected to the horizontally extending web portion 30 to which are integrally connected the members 22 and 23.

As can readily be seen when viewing FIG. 2, the piston 29 is spring returned by an axially positioned, helical spring 31. If a defective syringe is present when the switch 24 is actuated, the reject mechanism comprising the air motor 28 will operate to lower the members 22 and 23 which engage the flange portion F of the barrel B and pull the barrel from the retaining clips 11 and permit the defective syringe to drop vertically downward into a suitable discard chute (not shown).

As can be seen when viewing FIG. 3, the pressure switch 17 is connected to a time delay relay 32. The relay is normally set so that it will not block a reject signal to the reject mechanism when the switch 24 is closed unless the relay is actuated by the switch 17, then it will block the reject signal. Basically, the time delay relay comprises a timing motor and switch. As shown in the circuit diagram of FIG. 4, the time delay relay 32 is schematically represented by a motor winding 33 and switch 34.

Having described the mechanical operations of the mechanisms of the invention, the following description, with particular reference to FIGS. 3 and 4, will provide a clear understanding of the sequence of operation of the invention.

The staked syringe passes between the pressure switch 17 and the air nozzle 12, tripping the switch 15 which actuates the solenoid 13. Operation of the solenoid valve 13 will send a regulated air stream into the syringe. As pointed out previously, switch 15 is tripped by the needle so that if there is no needle the air is not turned on. When the air passes through the syringe, indicating a good, unclogged syringe needle, the pressure switch 17 closes to start the time delay relay 32 which is set, for example for .8 second. When the timer is actuated, the timer contact or switch 34 is opened and held open for the timing interval. When the syringe has travelled, for example .7 second after tripping the switch 15, it will trip the switch 24. Since the air passing through the good syringe, opened the timer contact or switch 34 by way of the pressure switch 17, the closing of the switch 24 will not actuate the solenoid 26. Thus the syringe will pass through the reject mechanism without being disturbed. When a plugged syringe is being inspected, it will also trip the switch 15 to turn on the air, but since the air will not pass through the syringe, the pressure switch 17 will not be actuated and the timer 31 will not start and its contacts 34 will remain closed. Then, when the syringe moves to trip the switch 24, and the circuit through the switch 34 is closed, the solenoid 26 will be actuated, causing operation of the motor 28 to reject the syringe. The .8 second mentioned above as the timing interval, is such that the timer will be closed again before the next syringe arrives at the inspection station. Obviously, the period of timing can be set to any desired time depending on the syringe spacing on the conveyor and the line speed.

In the event a syringe barrel comes into the inspection

station without a needle, the switch 15 will not be tripped and, therefore, the solenoid valve 13 will not be opened and no air will flow into the barrel B. In this situation, the pressure switch 17 will not be actuated, therefore, the time delay relay is not started. Since the time delay relay is not started, the switch 34 within the relay will remain closed and when the barrel reaches the reject position and closes the switch 24 the barrel without the needle will be ejected by the reject mechanism. Thus it can be seen that applicants have provided a method of testing and sorting staked syringes which is capable of selecting those syringes which are not properly made. Furthermore, the apparatus is automatic in its operation and simple in its execution, such that it does not require a great deal of maintenance and is capable of operating at relatively high speeds.

Furthermore, the invention may be used to sort on the basis of needle bore sizes. This may be done by adjusting the pressure regulator so that it will deliver to the syringe a flow of air of a velocity and at a pressure such that, for example, a 20-gauge needle will emit air under sufficient flow velocity to operate the pressure switch, but a 23-gauge needle will provide insufficient flow to trip the pressure sensing switch 17. This may be an important factor from the standpoint that during change over from one size syringe to another, there is the possibility that the needle supply to the assembling machine may inadvertently be supplied with needles of an improper gauge.

Other and further modifications may be resorted to within the spirit and scope of the appended claims.

We claim:

1. Apparatus for inspecting staked syringes for plugged needles comprising, an air nozzle positioned in axial alignment with the path of movement of the syringes, a source of air under pressure connected to said nozzle, a valve interposed said source and nozzle, switch means connected to said valve and mounted with its actuator in the path of movement of said needles, means at the opposite end of said syringes for sensing the presence of air exiting from the needles, means responsive to movement of the syringe past the inspection station for ejecting the syringes and means connected to said sensing means for inactivating said ejecting means.

2. Apparatus for inspecting staked syringes for plugged needles comprising, an endless chain having syringe barrel engaging clips carried thereby, a guide rail positioned to engage each individual syringe barrel as the barrel is moved into alignment with the nozzle, guide means positioned to simultaneously engage the needle to accurately position the staked syringes at the inspection station, means in the path of movement of said syringes for blowing air under pressure axially into the open end of said syringes, means at the opposite end of said syringes for sensing the presence of air exiting from the needles, means responsive to movement of the syringes past the inspection station for ejecting the syringes and means connected to said sensing means for inactivating said ejecting means.

3. Apparatus for inspecting staked syringes for plugged needles comprising, means for conveying a plurality of syringes in series, means in the path of movement of said syringes for blowing air under pressure axially into the open end of said syringes, means at the opposite end of said syringes for sensing the presence of air exiting from the needles, a syringe engaging member responsive to movement of the syringe past the inspection station, reciprocating motor means connected to said member for operating said member to eject faulty syringes, syringe engaging switch means connected to said motor for causing actuation of said motor, and means connected to said sensing means for inactivating said ejecting means.

4. The apparatus as set forth in claim 1, wherein said sensing means comprises, a pressure sensitive switch mounted in spaced, axially aligned relationship with re-

spect to said nozzle whereby the syringe under test is positioned therebetween.

5. The apparatus set forth in claim 4, wherein said means responsive to movement of the syringes past the inspection station comprises, a switch mounted in the path of movement of said syringes and actuated thereby, a time delay relay, a reject mechanism connected to a source of current through said switch and said time delay relay, and said pressure sensitive switch is connected to said time delay relay for actuating said relay.
